Inventor

UNITED STATES PATENT OFFICE.

RAYMOND GARBS, OF KANKAKEE, ILLINOIS.

FOLDING CRATE OR COOP.

Application filed September 15, 1926. Serial No. 135,629.

The present invention relates to a folding crate and aims to provide a novel and improved device of this character which can be conveniently and efficiently collapsed or 5 folded when not in use so as to take up a minimum amount of space, said crate being more particularly designed for use as a poultry coop for shipping poultry therein.

Another object of the invention is to provide a crate having its end walls hingedly connected to one of the side walls so that said end walls may be folded inwardly against the side wall when collapsing the crate, while the top and bottom walls each 15 comprise two sections pivotally connected to the side walls and hingedly connected together by links to fold inwardly, the aforesaid end sections when arranged in operative position and engaged by catches supporting 20 the top and bottom walls against folding or collapsing movement.

A further object of the invention is the provision of a folding coop or crate constructed of metallic strips for forming frames 25 in connection with slats or strips of wood or metal secured to said metallic members, said metallic frames being arranged to support the crate or coop at its corners as well as providing hinge connections for the various folding sections.

It is also an object of the invention to provide a coop or crate of the above indicated character, which is simple and substantial in construction, which can be manufactured 35 economically, and which will be thoroughly efficient and practical in use.

With the foregoing and other objects in view, which will be apparent as the description proceeds, the invention resides in the 40 construction and arrangement of parts, as hereinafter described and claimed, it being understood that changes can be made within the scope of what is claimed, without departing from the spirit of the invention.

45 The invention is illustrated in the accompanying drawings, wherein:

Figure 1 is a perspective view of my improved crate showing the same in operative arrangement,

50 Figure 2 is a horizontal section through the coop or crate,

Figure 3 is an end elevation of the same,

Figure 4 is a similar view showing the end walls folded inwardly,

55 Figure 5 is a similar view to Figure 4

illustrating the manner in which the top and bottom walls are folded,

Figure 6 is an end elevation showing the crate in folded or collapsed position,

Figure 7 is a fragmentary vertical section 60 taken on line 7—7 of Figure 3,

Figure 8 is a fragmentary vertical section taken on line 8—8 of Figure 3, and

Figure 9 is a fragmentary section taken 65 on line 9—9 of Figure 3.

In carrying out the invention, the letters A and B designate the top and bottom walls respectively, the letters C and D the side walls respectively, and the letters E and F the end walls. The various walls are formed 70 by series of slats or strips of light wood or the like, as indicated by the numeral 10, connected at their ends to metal angle bars, as hereinafter described.

Secured to the opposite ends of the slats 75 or strips 10 that form the side walls C and D are angled metallic members 11 and 12, those at the ends of the side wall C being designated by the numeral 11 while those secured to the side wall D are designated by the numeral 12, and they are attached to the slats or strips 10 by means of rivets 13, as indicated in Figure 8 of the drawings, or may be secured in any other desired manner. The angled metallic members 11 have extending 80 at right angles at each end thereof portions 14 and 15, which extend partially along the top and bottom walls respectively. The portions 14 and 15 are constructed from the main angled member 11 and are arranged at 90 right angles so as to provide means for rigidly supporting the corners of the crate or coop. The portions 14 and 15 are of different lengths, for a purpose which will be set forth as the description proceeds. Each of the 95 angled metallic members 12 also has a right angle extension 16 at its lower end serving the same purpose as the portions 14 and 15.

Hingedly connected to the ends of the portions 15 of the angled members 11 and to the portions 16 of the angled members 12 are angle bars 17 and 18 respectively, connected together by short link members 19. The portions 15 and 16 of the angled metallic members 11 and 12 and the angle bars 17 and 18 105 have secured thereto slats or strips 10 by means of rivets, or the like, for forming the bottom wall of the crate or coop.

The top wall A of the coop or crate is supported by angle bars 20 and 21 hingedly con- 110

nected at their outer ends to the portion 14 of the angled member 11 and the upper end of the angled member 12. The slats forming the top wall of the coop or crate are secured 5 to the portion 14 of the angled member 11 and to the angle bars 20 and 21, and the inner ends of the latter are pivotally connected together by a link 22.

It is to be noted by referring to Figure 2 of the drawings that a similar angle bar to that provided at the opposite ends of the slats or strips 10 is also provided intermediate their ends, as designated by the numeral 23, said intermediate angle bar having extensions 15 similar to the portions 14 and 15 of the angled member 11 and the portion 16 of the angled member 12 to permit the efficient folding or collapsing of the crate.

The slats or strips 10 forming the end walls 20 of the coop or crate have their opposite ends secured to uprights 24 and 25, the uprights 24 being hingedly connected, as at 26, to the slats or strips 10 forming the side wall C so as to permit said end walls to be folded inwardly and lie in close proximity to the inner side of said side wall, as shown in dotted lines in Figure 2 of the drawings. The end walls E and F are hinged to the side wall C by securing small plates 26^a to the top of the portion 14 and bottom of the portion 15 of the angled members 11 so that said plates extend over and under the uprights 24, with pivot pins 26^b extending through the plates and into said uprights 24. Arranged on the 35 ends of the end wall opposite to that where the same are hingedly connected to the side wall C are small latch or locking members 27 which are adapted to be turned over the outer faces of the angled metallic members 12 so as to hold the end walls E and F in extended or operative position. The end walls E and F also have secured thereto intermediate their ends at the tops and bottoms thereof metal catches 28 the bent ends 29 of which are 45 adapted to engage the links 22 of the top wall and the links 19 of the bottom wall, as clearly shown in Figure 1 of the drawings in order to properly hold the top and bottom walls A and B against movement when the end walls 50 E and F are in operative position.

On the angle bar 20 of the top wall a pair of removable slats or strips 10 are adapted to be placed to permit poultry to be put into and taken from the coop or crate, and so that these 55 slats or strips 10 may be removable a pair of metallic strips 30 are secured to the tops of permanent slats or strips 10 of the top for the slats or strips to be slid thereunder. Under each of the metallic strips 30 is a small block 60 31 for aiding in properly spacing said strips from the metallic sections 20.

Attached to the angled members 11 at the opposite ends of the crate or coop are bars 65 34 which extend parallel with the end walls E and F and have their free ends bent to form

hooks 35 for engaging the angled members 12 to hold the crate or coop in folded or collapsed position.

In operation, when it is desired to fold or collapse the crate the small latches or locking members 27 are turned so as to disengage the metallic, angled members 12. When the latch or locking members 27 are in this position, the end walls E and F may be swung on their hinge connections with the side wall C so as to lie in close proximity to the inner side of the side wall C, as shown in dotted lines in Figure 2 of the drawings and in full lines in Figures 4, 5, and 6 of the drawings. When the end walls are swung in such position, the metallic members 28 have disengaged the links 19 and 22 so that the metallic frames supporting the top and bottom walls A and B may also be folded. By referring to Figure 5 of the drawings, it can be seen how the top and bottom walls A and B are swung so as to fold the same. It is to be noted that by providing the portions 14 of the angled, metallic members 11 of relatively long length that the top wall A when folded will be spaced a sufficient distance from the side wall C so as to permit the folded bottom B to extend between said top wall A and side wall C when the crate is collapsed or folded. The lengths of the portions 14, 15, and 16 are sufficient to accommodate the thickness of the top and bottom walls A and B when folded. It can be seen that it is not necessary to provide a lateral extension at the upper end of the angled, metallic member 12 as the angle bar 21 and the strips or slats carried thereby will be folded in close contact with the side wall D, but, at the opposite side of the crate it is necessary to provide sufficient space to accommodate the end walls E and F. By providing the links 19 and 22, it can be seen that when the top and bottom walls A and B are folded they are of a length to accommodate the thickness of the slats or strips carried thereby. After the crate or coop is folded or collapsed, the hooks 35 on the bars 34 are engaged over the angled members 12 for holding the crate or coop in such position. When it is desired to unfold the crate to an operative position, the hooks 35 are disengaged from the angled members 12, the top and bottom walls A and B are swung upon their hinge connections and the end walls swung outwardly until the same engage the flanges of the metallic frames, as shown in Figure 8 of the drawings. By then swinging the latch or locking members 27 to engage over the flanges of the members 12, said end walls will be held in rigid or permanent position. During the swinging of the end walls outwardly, the angled portions 29 of the members 28 will engage over the links 22 and under the links 19 so as to hold the top and bottom walls A and B against swinging movement on their hinged connections.

From the foregoing, it can be seen that I have provided a crate which is strong and durable in use, and which may be folded or collapsed when not in use so as to take up a minimum amount of space in commission houses, trucks, express cars or any place it is desired to store the crate or coop, thereby saving considerable time and labor as well as storage space. The farmer or poultry raiser can take coops home in his car or truck saving him sufficient space to carry back home whatever he may need from the city, thereby saving him extra trips for supplies or the like.

Having thus described my invention, what I claim as new is:

A folding poultry coop comprising angle-iron corner posts to which the sides are attached, the corner posts at one side of the coop having inwardly projecting end extensions of different lengths and those at the

other side having inward extensions at the lower ends only, end sections pivotally adjoining the first mentioned corner post to fold inwardly against the side wall connected to said corner posts, a bottom comprising angle bars to the underside of which the boards are attached, said angle bars being pivoted to the lower extensions of the opposite corner posts, and links connecting the inner ends of the angle bars; together with a top comprising angle bars connected by links and to the upper side of which the slats are attached, metal catches engaging the aforesaid links when the parts of the coop are extended for use, and hook-ended bars attached to the ends of one of the side sections of the coop to engage the other side section of the coop in folded arrangement of the latter.

In testimony whereof, I have affixed my signature.

RAYMOND GARBS.
